UNITED STATES PATENT OFFICE.

CHRISTIAN L. CHESTER, OF MONESSEN, PENNSYLVANIA.

TORCH.

1,023,622.

Specification of Letters Patent.

Patented Apr. 16, 1912.

Application filed March 20, 1911. Serial No. 615,690.

To all whom it may concern:

Be it known that I, CHRISTIAN L. CHESTER, a citizen of the United States of America, residing at Monessen, in the county of 5 Westmoreland and State of Pennsylvania, have invented certain new and useful Improvements in Torches, of which the following is a specification, reference being had therein to the accompanying drawing.

10 This invention relates to torches for painters' use and has for its object to provide a device of such class in a manner as herein-after set forth which will allow of the painter manipulating the device with one 15 hand during the scraping of the paint from woodwork or other objects.

Although the device is designed primarily for the use of painters, yet it can also be employed by plumbers and tinsmiths for 20 heating and soldering when occasion so requires.

Further objects of the invention are to provide a torch for painters' use which shall be comparatively simple in its construction 25 and arrangement, strong, durable, efficient in its use, provided with means for coupling a scraping or soldering iron thereto in proximity to a burner, conveniently operated, and comparatively inexpensive to manufac- 30 ture.

With the foregoing and other objects in view, the invention consists of the novel construction, combination and arrangement of parts as hereinafter more specifically described and illustrated in the accompanying drawings wherein is shown the preferred embodiment of the invention, but it is to be understood that changes, variations and modifications can be resorted to which come 40 within the scope of the claim hereunto appended.

In describing the invention in detail, reference is had to the accompanying drawings wherein like reference characters denote cor- 45 responding parts throughout the several views and in which:

Figure 1 is a side elevation partly in section of a torch in accordance with this invention. Fig. 2 is a vertical sectional view thereof 50 partly in elevation. Fig. 3 is a horizontal sectional view, and, Fig. 4 is a sectional detail illustrating the tool-holder.

Referring to the drawings in detail, 1 denotes a cylindrical receptacle provided at 55 one end with a cap piece 1^a and at its other end with a cup-shaped bottom 1^b provided

with a filling opening 1^c surrounded by a mouth piece 1^d. The opening 1^c is closed by a removable plug 2 provided with a handle 2^a. The opening 1^c permits of the receptacle 1 which constitutes the body-portion of the device being filled with gasolene or any suitable hydrocarbon. 60

Connected to the cap piece 1^a at the perim- 65 eter thereof is an upright tool-holder 3 for positioning a tool in proximity to a burner 9. The tool holder 3 is hollow for the re- ception of the shank of the tool and extending through the tool holder 3 and engaging the shank of the tool is a set screw 3^a where- 70 by the tool is fixedly secured in the tool holder. In Fig 4, the tool is illustrated as a soldering iron 4 provided with a shank 4^a and in Figs. 1 and 2 the tool is shown as a scraping iron 5 provided with a shank 5^a. 75

Extending through the cap piece 1^a into the body-portion 1 is a feed pipe 6. That portion of the pipe 6 which is arranged within the body-portion 1 is enlarged as at 7 and is reduced at its lower end to provide 80 a goose neck 8 having an inlet opening 8^a. Mounted upon the pipe 6 exteriorly of the body-portion 1 is an elbow 6^a to which is attached a coupling 6^b for connecting the burner 9 with the pipe 6. The burner 9 is 85 provided with a regulating valve 10.

Connected to the elements 1^a and 1^b by the coupling members 10^a is a pump formed of a cylinder 11 closed by cap pieces 10^b, 10^c which are formed integral with the cou- 90 plings 10^a. Within the cylinder 11 operates a piston 11^a which is connected to a piston rod 11^b projecting from the lower end of the cylinder 11 and provided with a hand grip 11^c. The cylinder 11 communicates with the upper part of the body-portion 1 by a pipe 12 which opens into the cylinder 11 through the cap piece 10^c and opens into the upper part of the body-portion 1 through the cap piece 1^a and upper end of the body-portion 1. The pump is used for forcing air into 100 the upper end of the body-portion 1 so as to place hydrocarbon contained in the body-portion 1 under pressure.

The function of the goose neck 8 is to 105 allow practically the entire amount of gaso- len to be removed from the receptacle 1. When the torch is used, it is held in an in- clined position, that is, at an acute angle to a vertical piece of work. Under such con- 110 ditions, the gasolene will be held at the lower end of the receptacle near the end of the

goose neck and practically the entire amount of gasoline will be utilized.

The function of the enlargement 7 within the receptacle 1 is to hold approximately 5 one-third of the gasoline within the torch, and when the torch is used in an inverted position, this one-third volume of gasoline is sufficient to supply the torch for a short period during its inverted use. If there 10 was only a small quantity of gasoline within the pipe 6, the torch would soon be extinguished.

When the torch is to be placed in operation, the pump is actuated to force enough 15 of the contents of the casing 1 through the tube 7 into the burner, the valve 10 is then regulated whereby oil will properly burn to produce a flame at the scraper 5. The flame melts the paint upon the surface and 20 the scraper 5 follows in the path of the flame and removes the paint.

What I claim is:

A torch comprising a body portion for containing a hydrocarbon, a pipe arranged within and projecting from said body portion and having that part within the body portion enlarged and terminating in a goose neck said enlarged part of said pipe holding a supply of hydrocarbon to permit of the operation of the device when it is inverted, said goose neck provided with an inlet, a regulatable burner connected to the upper portion of said pipe, a tool holder for positioning a tool relative to the burner, and an air pump carried by said body portion and opening into the upper end thereof. 25 30 35

In testimony whereof I affix my signature in the presence of two witnesses.

CHRISTIAN L. CHESTER.
